UNITED STATES PATENT OFFICE.

JOHN FANNING AND EDWARD NUGENT, OF BROOKLYN, NEW YORK.

IMPROVEMENT IN SEWING-MACHINES.

Specification forming part of Letters Patent No. **145,287**, dated December 9, 1873; application filed November 1, 1873.

To all whom it may concern:

Be it known that we, JOHN FANNING and EDWARD NUGENT, of the city of Brooklyn, in Kings county, in the State of New York, have invented certain Improvements in Sewing-Machines, of which the following is a specification:

Our invention relates to the mode of constructing that class of sewing-machines known as the "elastic lock-stitch machines," our object being to construct a machine that can be more readily and perfectly adjusted than those hitherto made.

It is well known among operators that a great difficulty exists in adjusting this class of machines to different kinds and sizes of thread, and prevent dropping stitches. This objection is entirely avoided in our machine.

The following is a full and exact description of our machine, reference being had to the accompanying drawings and to the letters of reference marked thereon, in which—

Figure 1 is a top view of our machine. A is the needle-bar. B is the pressure-foot bar. C is the tension for the upper thread. D is the tension for the lower thread.

Fig. 2 is a side elevation of our machine. E is the under or horizontal needle. F is a screw passing through a slot in the bar G into the end of the needle E, to enable the operator to adjust the needle E lengthwise. H is an os-

cillating bearing or guide for adjusting the needle sidewise. I is the driving-shaft. J J are beveled gear-wheels, giving motion to an eccentric, K, which drives the under needle-bar G. This oscillating bearing is composed of a plate, o, having a pin or journal secured in the forward bearing of the main shaft, and adjustable by means of a screw, h, so as to place the needle E in proper relation with the vertical needle; and at top of plate o is a pivoted block, i, having a hole to receive and guide the needle steadily.

Fig. 3 is an elevation of the back end of our machine, showing the eccentric L, which gives motion to the upper needle-bar, communicating said motion through the arm N.

Fig. 4 is a front-end elevation of our machine, in which M is the feed-bar.

Having thus described our invention, what we claim as new, and desire to secure by Letters Patent, is—

The oscillating adjustable guide H, constructed as described, in combination with the eccentric K, bar G, and needle E, operating in connection with an eye-pointed perforating-needle, as and for the purpose described.

JOHN FANNING.
EDWARD NUGENT.
